UNITED STATES PATENT OFFICE.

THOMAS H. SEELY, OF MALDEN, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON SOLES.

1,344,063.

Specification of Letters Patent. Patented June 22, 1920.

Application filed March 19, 1918. Serial No. 223,373.

To all whom it may concern:

Be it known that I, THOMAS H. SEELY, a citizen of the United States, residing at Malden, in the county of Middlesex and State of Massachusetts, have invented certain new and useful Improvements in Machines for Operating on Soles; and I do hereby declare the following to be a full, clear, and exact description of the invention, such as will enable others skilled in the art to which it appertains to make and use the same.

The present invention relates to machines for operating on soles which are used in the manufacture of boots and shoes, and more particularly to machines for operating on soles provided with a marginal rib or lip, such, for example, as welt insoles.

The invention is illustrated as embodied in a rib tightening machine by which the fabric on a reinforced insole is set firmly against the rib, more particularly at the base of the upstanding rib where it joins the body of the insole. Certain features of the invention, as will be recognized by those skilled in the art from the following description, are not limited to use in a machine for performing the rib tightening operation but may be employed advantageously in other types of machines for applying reinforcing fabric to insoles; and certain features of the invention may be employed with equal advantage in machines for operating upon lipped insoles whether or not reinforcing fabric is applied thereto.

One type of machines for operating upon lipped insoles, feeds the work by means of two rolls which engage the opposite sides of the feather. It has been found difficult with such machines to turn a pointed toe sole around the end of the toe, as heretofore the feeding rolls have been so constructed and arranged that, on the turn, they tend to continue to feed the work in a straight line, thus causing the inside lip tool to strain the lip outwardly when engaged at the point of the toe. One object of the present invention is to overcome this difficulty and to produce a machine which will enable the operator to guide the sole easily around the end of the toe. To the accomplishment of this object, one feature of the invention contemplates the provision of feeding means constructed to impart a greater feeding

movement to the outer margin of the feather than is imparted to its inner margin. Such feeding means, it will be observed, provides a normal tendency to feed the work in a circular path.

Another object of the invention is to improve the construction and mode of operation of the lip engaging tools whereby a firm but yielding pressure may be applied to the lip for the purpose of tightening the rib of a reinforced insole, or molding the lip of an all leather insole.

To the accomplishment of these objects and such others as may hereinafter appear, as will readily be understood by those skilled in the art, the invention comprises certain devices, combinations and arrangement of parts hereinafter described and particularly pointed out in the appended claims.

The various features of the present invention will be best understood from an inspection of the accompanying drawings illustrating the preferred embodiment of the invention, in which:

Figure 1 is a side elevation of the machine;

Fig. 2 is a section on the line 2—2 of Fig. 1; and

Figs. 3 and 4 are detail views, in section, showing the relation of the work engaging tools and the insole at different times in the cycle of the machine.

In the illustrated embodiment of the invention, the work is fed by two positively driven rolls 10 and 12 (Figs. 1, 3 and 4); the roll 10 forming the work support which co-acts with the feed roll 12 to grip the feather of the sole therebetween on a line transverse to the line of feed and feed the work in a manner to gain the advantage hereinbefore adverted to. To this end the feather engaging portions 14 of the rolls are in the form of truncated cones which, if completed, would have their apexes approximately coinciding at a common point 16 above the interior of the sole at its wider parts. The two rolls being driven at equal peripheral speeds, as will be described, it is apparent that the greater diameter of the conical surfaces 14 engaging the outer edge of the feather will tend to feed that portion of the feather at a greater speed than the portion near the base of the lip which is engaged by the smaller diameter of the conical

surfaces 14. By this construction if the sole is unrestrained, either by the hand of the operator or the engagement of the lip with the generally vertical face of the feed roll 12, the sole tends to feed in a circular path about an axis passing substantially through the point 16. When the end of the toe is reached any slight guiding pressure exerted upon the sole will cause it to turn about a center coinciding with the radius of the toe and thus overcome the injury or deformation of the lip which has heretofore taken place.

The toe work engaging rolls are arranged 15 to be separated to permit the insertion and removal of work without cessation of their feeding movement. To this end the work supporting roll 10 is mounted on a stud 24 clamped in the split end of a pivoted arm 26, by a cap screw 28. The arm 26 (Figs. 1 and 2) is loosely mounted on the main driving shaft 18 between the sides of the machine frame 30 and may be lowered to free the work but is normally urged upwardly, 25 so as to grip the insole feather between the rolls 10 and 12, by a spring 32 housed in the arm backed by a plunger 34 bearing against the machine frame 30. The lower end of the hub of the work supporting roll 10 is 30 provided with an integral worm gear 36 which meshes with a worm 38 fixed on a shaft 40 mounted in suitable bearings in the arm 26. The shaft 40 is arranged to be driven by the main driving shaft 18 through 35 a pair of spur gears 42 and 44 inclosed by a cover 46. The upward movement of the arm 26 under the action of the spring 32 is limited, when there is no work in the machine, by a pair of lock nuts 52 on a treadle 40 rod 54 which engage the lower side of a lug 56 on the column 58. The treadle rod is connected, at its upper end, with the arm 26 and its lower end is provided with a suitable treadle (not shown) by which the arm may 45 be depressed to separate the rolls to enter and remove the work. The downward movement of the arm is limited by an adjustable collar 60 on the treadle rod 54 so as to prevent the worm 38 from being drawn out of 50 mesh with the worm gear 50. The inoperative portion of the work supporting roll 10 is inclosed by a work rest 62 mounted on the arm 26.

The feed roll 12 is secured to one end of a 55 shaft 48 mounted in a bearing in the frame 30. The other end of the shaft 48 carries a worm gear 50 which meshes with the worm 38, both rolls thus being driven from a single source of power. By the proper ratio 60 of gearing the rolls 10 and 12 have equal peripheral speeds thus producing a relative rolling movement. The shaft 18 is provided with the usual tight and loose pulleys 20 and 22 for belt connection with a source of 65 power.

The feature of this invention which relates to the lip engaging tools resides in the construction and mode of operation of a tool 64 which co-acts with the face 66 of the feed roll 12 to compress the lip thereby firmly applying the fabric to the entire surface of the lip. The tool 64 is arranged to pound the lip, with a yielding blow, as it is fed by the rolls 10 and 12. The lower end of the tool 64 is properly formed to produce the desired shape of the lip and the face 66 of the feed roll 12 is given a formation complementary to that of the tool 70 and forms an outside lip support. As illustrated in Fig. 3 the lower end of the tool 80 may be provided with an enlarged head 68 to enter the angle between the lip and the body of the sole thereby providing for molding the lip inward toward the center of the sole. The upper end of the tool is provided 85 with an enlarged shank 70 which is loosely seated in a recess 73 in a lever 72 pivotally mounted on a stud 74 in the machine frame. The other end of the lever 72 is connected, through an eccentric stud 76 which is secured in adjusted position by a cap screw 78, with an eccentric link 80 actuated by an eccentric 82 (Figs. 1 and 2) formed on the hub of the worm 38. By this construction 90 a series of rapid oscillations is imparted to the tool 64 during the operation of the machine.

Provision for causing the blow of the tool to be of a yielding nature is obtained by the manner in which the tool is mounted in 100 the lever 72 which, in effect, is a ball and socket connection. The shank 70 of the tool is of the general shape of a cone having its apex and base rounded. A plunger 84 (Figs. 3 and 4) is loosely mounted in the recess 73 and at the center of its lower surface it is provided with a cupped seat for the rounded top of the shank 70. A finger 86, pivotally mounted on the lever 72, rests on the upper end of the plunger 84. A rod 90 bears on the finger and is pressed downwardly by a spring 92 set into the arm 72. Thus the plunger tends to keep the shank 70 centrally positioned with its rounded upper end in the seat in the plunger as 110 shown in Fig. 4. When the lower end of the tool strikes the lip, however, the tool is tilted against the force of the spring 92, about an axis near one side of the base of the conical shank 70 which axis will be over 115 and slightly above the lip as shown in Fig. 3. The relative proportions of the recess 73 and the seat for the rounded top of the shank 70 are such that the top of the shank will never be wholly removed from the seat, thus as soon as the pressure on the lip is removed the downward spring pressure of the plunger 86 will again centralize the position of the tool. The path of travel of the tool 64 may be adjusted to accommodate 120

5 lips of different thickness, by means of the eccentric stud 76. The force of the blow of the tool may be varied by adjusting the screw 96 which forms the rigid abutment 5 for the spring 92.

10 The work supporting roll 10 is provided with a second conical surface 94 which supports the sole below and inside the line of the lip thereby bending the feather at an angle to the body of the sole as shown in 10 Figs. 3 and 4.

15 As will be apparent from an inspection of Fig. 1, when the treadle is depressed for the removal or insertion of work the arm 26 and, perforce, the shaft 40 will be moved downwardly. As this shaft carries the eccentric 82 bodily in a downward direction, it will swing the lever 72 and thus move the tool 64 in a substantially horizontal 20 plane away from the roll 12 to allow room to insert or remove the lip.

25 The nature and scope of the present invention having been indicated and its preferred embodiment having been specifically described, what is claimed as new is:

30 1. In a machine for operating upon lipped soles, a pair of frusto-conical feed rolls having their apexes substantially coinciding arranged to grip and feed the feather between their conical surfaces and having their smaller faces directed toward each other and the center of the sole.

35 2. A machine for operating on lipped soles having, in combination, a work supporting roll having a frusto-conical feather supporting surface and a second conical surface to support the sole inside of the feather, and a feed roll having a frusto-conical feather engaging surface, the apex of which approximately coincides with the apex of the frusto-40 conical feather supporting surface.

45 3. A machine for operating on a sole having an upstanding lip having, in combination, a tool for operating at the inner face of the lip, and sole feeding means constructed and arranged to impart a greater feeding movement to the periphery of the sole than is imparted to the inner portions of the sole to act similarly on both sides of the sole 50 to impart the same feeding movement to both sides of the sole.

55 4. A machine for operating on lipped soles having, in combination, a tool for operating at the inner face of the lip, and a pair of rolls to grip and feed the feather therebetween having their feather engaging surfaces in the form of truncated cones both arranged with their larger bases directed away from the center of the sole and having the smaller 60 peripheries of said conical surface portions in substantial coincidence at their points of contact.

65 5. A rib tightening machine for reinforced insoles having, in combination, mechanism for pressing reinforcing fabric into

the angles at the base of the rib comprising inside and outside tools, and rolls positively driven at the same surface speeds for feeding the insole past said tools tending continually to swing the insole in a path extending in an arc curved about the inner tool.

70 6. A rib tightening machine for reinforced insoles having, in combination, reinforcing fabric pressing tools at each side of the rib, said tool at the inner side of the rib comprising a roll and said tool at the outer side of the rib comprising a truncated cone bearing with its circumferential surface on the feather, and a co-operating insole supporting and feeding roll comprising a truncated cone 75 the circumferential surface of which engages the feather opposite said outside pressing tool, the larger bases of said cones being directed away from each other and the center of the sole, said cones having their apexes in 80 substantial coincidence.

85 7. A machine for operating on soles having, in combination, a feed roll, a work supporting roll, a single means for rotating the rolls, and means for moving one of the rolls 90 and the rotating means toward and from the other roll.

95 8. A machine for operating on lipped soles having, in combination, a pair of work feeding rolls, a vibratory lip engaging tool having its pivot in fixed relation with one of the rolls, means having a fixed relation with the other roll for actuating the rolls and the tool, and means for relatively separating the rolls and the tool from each other.

100 9. A machine for operating on lipped soles having, in combination, a work supporting roll mounted on a pivoted arm, a feed roll, a vibrating lip engaging tool, actuating means carried by the arm for rolls and 105 the tool, and means for moving the arm and separating the tool from the roll through the agency of said actuating means.

110 10. A machine for operating on lipped soles having, in combination, a work supporting roll mounted on a pivoted arm, a feed roll, a lip engaging tool mounted to oscillate about a fixed point, a shaft carried by the arm and provided with a single actuating means for the rolls, an eccentric 115 secured to the shaft and operatively connected with the tool, and means for moving the arm about its pivot to depress the work supporting roll and move the tool away from the feed roll.

120 11. A machine for operating on lipped soles having, in combination, a lip support, a lip engaging tool extending substantially vertical to the body of the sole, means for bodily reciprocating the tool to compress the 125 lip against the lip support, and means to permit the tool to tilt about an axis at right angles to the line of its length.

130 12. In a machine for operating on lipped soles, a lip engaging tool having a ball and

- socket connection with its supporting means, and means acting to yieldingly hold the tool and its supporting means in a predetermined relation.
- 5 13. In a machine for operating on lipped soles, a lip engaging tool having a shank, means for imparting a positive reciprocating movement to one part of the shank, and means acting on another part of the shank 10 for yieldingly holding the tool in a predetermined relation to its actuating means.
14. In a machine for operating on lipped soles, a lip engaging tool having a conical
- shank, a reciprocating member loosely engaging the base and periphery of the shank, 15 a plunger having a seat for the apex of the conical shank, and a spring acting to retain the apex of the shank within the seat.
15. A machine for operating on lipped soles having, in combination, a driving 20 shaft, an arm pivotally mounted thereon, a work supporting roll carried by the arm, a feed roll, a lip engaging tool, and means mounted on the arm for operatively connecting the driving shaft and the rolls and tool. 25

THOMAS H. SEELEY.
